UNITED STATES PATENT OFFICE.

EDOUARD JEAN MARCEL MARTINI, OF PARIS, FRANCE.

DRYING APPARATUS.

1,215,951.

Specification of Letters Patent. Patented Feb. 13, 1917.

Application filed July 5, 1913. Serial No. 777,461.

To all whom it may concern:

Be it known that I, EDOUARD JEAN MARCEL MARTINI, of 2 Rue Charles Cazin, in the city of Paris, Republic of France, have invented an Improved Drying Apparatus, of which the following is a full, clear, and exact description.

The apparatus used for drying solid materials usually comprise a digester, in which 10 vacuum may be created, connected by a branch to a cooling apparatus in which the vapors from the materials to be dried are condensed.

With the apparatus thus arranged, it is 15 necessary to create a continuous circulation of the air and vapors by means of suitable devices, for instance by means of pumps which necessitate a constant maintenance of the vacuum if this vacuum is necessary and 20 do not allow to operate in a closed aseptic medium.

The present invention has for its object an apparatus allowing to obtain the rapid drying of solid materials and to operate this 25 drying in a closed aseptic medium.

This invention is characterized by a device allowing a continuous circulation of the air and vapors, capable of being self-maintained without the help of any pump 30 or any other apparatus of this kind, and in a closed aseptic medium.

In this drying apparatus, the air and vapors heated in the digester tend to rise and to flow into the cooling apparatus in 35 which they are condensed.

The cooled air then falls back to the bottom of the cooling apparatus from which it returns to the digester.

The present invention has also for object 40 a form of hydraulic joint.

The invention is illustrated by way of example in the accompanying drawing in which:

Figure 1 shows in longitudinal vertical 45 section the apparatus in its entirety.

Fig. 2 shows apart and at a greater scale the hydraulic joint.

Fig. 3 is a diagrammatic view showing means for creating the vacuum in the apparatus, the view also showing means for maintaining the low temperature in the 50 cooling apparatus.

Fig. 4 is a cross-section of the digester.

In the drawing, the drying apparatus 55 forming the subject-matter of the present invention comprises a digester *a* provided

with a double casing *b* forming an annular chamber *c* in which circulates hot water.

This water enters the chamber *c* through a conduit *d* and issues from said chamber 60 through another conduit *e*.

The digester *a* is closed by a cover *f* provided with a joint of special arrangement which will be described hereafter.

Within the digester are arranged hurdles 65 or screens *1* and metal plates *2* forming movable walls allowing to divide it into compartments. These plates are covered with a coating appropriate to increase their emissive power, the said plates by radiation 70 promoting the heating of the substances to be dried. These substances can be suspended on suitably arranged rods or bars *3*.

The arrangement of the screen *1*, plates *2* and bars *3* may be as shown in Fig. 4, the 75 screen being arranged horizontally at the center of the digester and supported at its sides and the plates *2* being arranged transversely of the digester and suspended at their upper ends from the rods *3*.

The latter communicates through two branches *g* and *h* with a cooling apparatus *i* comprising a bundle of tubes *j* secured on two metal plates *j¹* and *j²*, and two chambers *k* and *k¹* are situated between these plates 85 and the ends of the cooling apparatus. The branches *g* and *h* open respectively at the upper part and at the lower part of the digester into the space inclosing the tubes *j*.

The cooling liquid, such as brine, enters 90 the chamber *k¹* through a conduit-pipe *l*, passes through tubes *j*, enters into the chamber *k* and issues from the apparatus through a pipe *m*.

A branch *n* arranged on the side of the 95 cooling apparatus and communicating with the space between the plates *j* and *j¹* allows the creation of a relative vacuum in the apparatus. The condensed liquid flows out through a pipe *n¹* into a vessel *n²*.

As shown in Fig. 3 the vacuum is created by a vacuum pump *w* connected with the branch pipe *n*, the latter being provided with a valve *x*. This figure also shows a casing *y* surrounding the cooling apparatus 105 *i* for receiving either a cooling mixture, as shown, or other means (coil, etc.,) adapted to maintain a temperature inferior to zero degree centigrade in the cooler.

The operation of the apparatus thus arranged is as follows:

At the beginning of the operation, after

the products to be dried are placed in the closed digester, they have been exteriorly sterilized, if necessary, as well as the ambient air, by a suitable volatile antiseptic current, 5 for instance sulfurous acid, that is afterward replaced by air or a sterile gas. The inlet of this air or gas is then cut off and vacuum is created at the same time as the digester or drying chamber *a* is heated. It 10 is to be understood that after the relative vacuum is created in the digester the pump *w* is cut off from the digester by the valve *x*.

Under the influence of the heat and of the vacuum, an evaporation of the liquids 15 contained in the materials to be dried is produced, the vapors thus produced pass through the branch *g*, enter the cooling apparatus and are condensed therein, said apparatus being at a temperature lower than 20 0°. At the same time the antiseptic is eliminated.

The air or gas charged with these vapors dries, and, through the branch *h* passes back through the drying chamber *a*. This 25 current of dry air, coming into contact with the materials to be dried, frees them from their moisture and is again sucked by the cooling apparatus and so on.

A real circulation of the air is thus obtained, this air charged with vapors passing in the cooling apparatus and coming back dry in the digester where it accelerates the evaporation.

The drying of the materials, by means of 35 the present apparatus, is therefore obtained by the combined action of the heat and of the current of dry air, which allows of drying rapidly and in an aseptic manner said materials.

40 As mentioned above, the cover *f* of the digester is provided with a hydraulic joint insuring an absolutely tight closure. This form of joint is illustrated in detail in Fig. 2.

45 As shown in this figure, the digester *a* presents at its end a reinforced part *a*¹ comprising a circular groove *o* of small depth, at the bottom of which is placed a rubber washer *p*. The outer edge of this 50 part *a*¹ is provided with a circular recess *q* partly covered by a ledge *a*² integral with the part *a*¹.

On the other hand, the cover *f* comprises internally two concentric circular flanges *r* and *s* one of which is adapted to enter the groove *o* and the other comes opposite the ledge *a*² so as to constitute the extension of the latter.

At any point of the periphery of the

cover is arranged a conduit *t* opening opposite the recess *q*.

When the cover *f* is closed and held by means of a rocking screw or of any other suitable device, the flange *r* presses on the elastic washer *p*. A rubber ring *u* of suitable strength is then placed on the joint existing between the ledge *a*² and the flange *s*. A liquid is then sent, through the conduit *t*, into the space formed by the recess *q* and limited by the parts *a*² and *s* and when this capacity is entirely filled, there is obtained a hydraulic joint absolutely preventing any reentrance or any issue of the air in the apparatus.

The above arrangements are only given by way of example, the forms, sizes and detail devices may be varied according to circumstances without modifying the principle of the invention.

Claims:

1. In a drying apparatus, a heated digester, a cooling apparatus connected to said digester, means for creating vacuum in the whole of the digester and of the cooling apparatus, and means for maintaining the cooling apparatus at a temperature inferior to 0° C.

2. In a drying apparatus, a heated digester, a cooling apparatus connected to said digester by two very short branches, 90 one at the upper part, the other at the lower part of the digester and of the cooling apparatus, whereby a continuous circulation of the mixture of air and vapors is produced, the heated mixture issuing by itself from the digester through the upper branch and flowing into the cooling apparatus, and the air cooled and freed from the vapors by the cooling apparatus returning to the digester through the lower branch, means 100 for maintaining the cooling apparatus at a temperature inferior to 0° C., and means for creating vacuum in the whole of the digester and of the cooling apparatus.

3. In a drying apparatus, a heated digester, a cooling apparatus connected to said digester, and metal plates in the digester dividing the digester into compartments, the said plates having a special coating for promoting the radiation.

The foregoing specification of my improved drying apparatus, signed by me this 23rd day of June 1913.

EDOUARD JEAN MARCEL MARTINI.
